UNITED STATES PATENT OFFICE.

EDWARD ELSWORTH LEEPER, OF COUNCIL BLUFFS, IOWA.

DESIGN FOR A MEDICINE-CARTON.

58,919.

Specification for Design.

Patented Sept. 6, 1921.

Application filed January 3, 1921. Serial No. 434,812. Term of patent 3½ years.

To all whom it may concern:

Be it known that I, EDWARD ELSWORTH LEEPER, a citizen of the United States, residing at Council Bluffs, in the county of Pottawattamie and State of Iowa, have invented a new, original, and ornamental Design for a Medicine-Carton, of which the following is a specification, reference being had to the accompanying drawing, forming a part thereof.

Fig. 2 is a top view of the same.

I claim:

The ornamental design for a medicine carton, as shown.

In testimony whereof, I have affixed my signature in presence of two witnesses.

EDWARD ELSWORTH LEEPER.

Witnesses:

ARTHUR H. STURGES,
HIRAM A. STURGES.
